UNITED STATES PATENT OFFICE.

ALWIN PAGE, JR., OF BELLEVUE BOROUGH, PENNSYLVANIA.

SIDE BEARING.

1,214,580.

Specification of Letters Patent.

Patented Feb. 6, 1917.

Application filed June 6, 1916. Serial No. 101,902.

To all whom it may concern:

Be it known that I, ALWIN PAGE, Jr., a citizen of the United States, and residing in Bellevue Borough, in the county of Allegheny and State of Pennsylvania, have invented or discovered new and useful Improvements in Side Bearings, of which the following is a specification.

My invention consists in certain new and useful improvements in side bearings for railway cars.

The object in view is the provision of a side bearing which will effectively reduce the friction, relieve the side thrust on the wheel flanges and rails, and prevent binding and uneven wear of the bearing and the surface with which it comes in contact.

For the accomplishment of these purposes, I provide a bearing socket, which may be attached to either the truck bolster or body bolster of the car, in which a roller is mounted to travel longitudinally. The roller is supported at its ends by means of anti-friction balls engaging substantially semi-spherical seats in the ends of the roller and traveling in raceways which may be of substantially semi-spherical cross section in the side walls of the socket or in bearing blocks carried thereby. For the purpose of elevating the roller toward either extremity of its travel said raceways are curved upwardly toward their ends. To enable the roller to roll or rock longitudinally, sufficient play is provided between the ends of the roller and the side walls of the socket or the bearing blocks.

Other novel features of construction and arrangement of parts will appear from the following description.

In the accompanying drawings, which are intended merely to illustrate the principles of my invention, but not to limit the same to the construction shown, Figure 1 is an end view showing my bearing applied to a truck bolster; Fig. 2 is a plan view of the same; Fig. 3 is a sectional view taken along the line III—III in Fig. 2; Fig. 4 is a sectional view taken along the line IV—IV in Fig. 2; Fig. 5 is a sectional view of a modification taken along the line V—V in Fig. 6, and Fig. 6 is a reduced plan view of said modification.

The following is a detailed description of the drawings, reference being first had to Figs. 1, 2, 3 and 4.

A represents the truck bolster and B the

bearing plate mounted on the body bolster of a railway car.

C is a casting having a base 1 provided with holes 2 through which bolts or rivets 3 pass to secure the casting to the bolster.

4 represents a pair of parallel longitudinal or side walls integral with the base 1 and set in from the edge thereof.

5 represents a pair of parallel end walls 65 connecting the side walls 4, and thus inclosing a rectangular socket.

6 represents buttress flanges which support and strengthen the walls of the socket.

D represents bearing blocks, preferably 70 drop forgings, which are secured, as by bolts 7, to the inner faces of the side walls 4, leaving between them a runway of somewhat greater width than the length of a roller E.

In the adjacent faces of the blocks D are 75 provided raceways 8 which are shown as of somewhat less than semi-spherical cross section, and, preferably curved upwardly from their centers toward their ends. The ends of the roller E are provided with somewhat 80 less than semi-spherical seats 9, and in each of said seats 9 is mounted a spherical ball 10, which also engages the adjacent raceway 8.

It is thus evident that the roller is supported at its ends and may roll freely along the raceways, rising as it moves away from the center of its runway in either direction. Both the roller E and the balls 10 are preferably drop forged.

The operation of the bearing is as follows: As the car swings on a curve and the plate B is depressed into contact with the roller E, the turning of the truck in relation to the car body will cause the roller to travel along its runway, rising as it moves and thus tending to force the car body back into the normal horizontal position. This lessens the thrust on the wheel flanges and track rails. Inasmuch as the body bolster is moving out of the horizontal when the bearing is engaged, if the roller were not free to rock or roll longitudinally of itself, the lateral thrust exerted on the roller would cause it to bind in its runway and result in uneven wear of the roller and the plate B. However, the play between the ends of the roller and the blocks D permits the roller to turn or rock longitudinally out of the horizontal so as to maintain a full length contact with the plate B. This action reduces the friction and renders the wear uniform for the

full length of the roller. I regard a quarter inch play at either end of the roller as sufficient. To prevent the accumulation of water or dirt in the runway, I provide the 5 end walls with bottom slots 11 at the ends of the runway.

In Figs. 5 and 6, I show the forged blocks D omitted and the side walls 4 thickened and strengthened so that the raceways 8 may be 10 provided in said walls themselves. To enable the bearing to be assembled in this type I make the casting C in two parts joined together longitudinally by means of twin flanges 12 through which pass the bolts or 15 rivets 13. In the type shown in Figs. 5 and 6, chilled castings are used.

The construction of the bearing is simple and durable and worn or broken parts may be readily replaced at little expense or trouble. 20

What I desire to claim is:—

1. A side bearing comprising a base member provided with a runway, the side walls of which runway are provided with raceways, a roller adapted to travel in said runway and having a ball seat in each of its 25 ends, and balls supporting the roller by engaging said seats and said raceways.

2. A side bearing comprising a base mem- 50

ber provided with a runway, the side walls 30 of which runway are provided with raceways curving upwardly toward their ends, a roller adapted to travel in said runway and having a ball seat in each of its ends, and balls supporting said roller by engaging said 35 seats and said raceways.

3. A side bearing comprising a base member provided with a runway, the side walls of which runway are provided with raceways, a roller of proper length to loosely fit 40 in said runway and having a ball seat in each of its ends, and spherical balls engaging said seats and said raceways whereby said roller is free to travel along said runway and to rock longitudinally. 45

4. A side bearing comprising a base member provided with a runway, the side walls of which runway are provided with raceways curving upwardly toward their ends, a roller of the proper length to loosely fit in 50 said runway and having a ball seat in each of its ends, and balls engaging said seats and said raceways whereby said roller is free to travel along said runway rising toward the ends of its travel and to rock longitudinally. 55

Signed at Bellevue, Pa., this 31st day of May, 1916.

ALWIN PAGE, JR.
